[57] CLAIM

The ornamental design for a combined support stand and power supply for cordless hair curling iron, as shown and described.

DESCRIPTION

FIG. 1 is a reduced rear perspective view of a combined support stand and battery charger for cordless hair curling iron showing my new design.

FIG. 2 is a top plan view of same;

FIG. 3 is a side elevational view of same, the other side being substantially identical;

FIG. 4 is a front elevational view of same;

FIG. 5 is a rear elevational view of same; and

FIG. 6 is a bottom plan view of same.

*Fig. 1.**Fig. 2.**Fig. 3.**Fig. 4.**Fig. 5.**Fig. 6.*
